Y. MATUNAGA

CONTROL OF VAPOR ELECTRIC DEVICES

Filed Oct. 9, 1926

Inventor:
Yosinobu Matunaga;
by *Alphonse J. Laut.*
His Attorney.

UNITED STATES PATENT OFFICE.

YOSINOBU MATUNAGA, OF TOKYO, JAPAN, ASSIGNOR TO GENERAL ELECTRIC COMPANY, A CORPORATION OF NEW YORK.

CONTROL OF VAPOR ELECTRIC DEVICES.

Application filed October 9, 1926, Serial No. 140,649, and in Japan December 30, 1925.

My invention relates to the control of vapor electric devices, and has for its principal object the provision of an improved apparatus whereby the arc of such a device 5 may be maintained irrespective of variation in the load and temperature conditions under which it is operated. A further object is the provision of means for ensuring quick 10 starting and smooth operation of a vapor electric device, such as a mercury rectifier or the like.

It is known that the current required to maintain an arc in the mercury rectifier is dependent on the temperature at which the 15 rectifier is operated. Thus, upon a decrease in the operating temperature of the rectifier, the pressure of the mercury vapor decreases, the voltage between the cathode and anode increases, and the arc is eventually extinguished unless means are provided for preventing too great a decrease in current. In 20 accordance with my invention, this difficulty is avoided by the provision of means operable to vary the exciting current of the rectifier in a manner to ensure continuity of the arc under the various load and temperature conditions to which the rectifier is subjected.

My invention will be better understood from the following description when considered in connection with the accompanying 30 drawing, and its scope will be pointed out in the appended claims.

The drawing shows a rectifying apparatus to which my invention has been applied.

This apparatus comprises a mercury rectifier 1 provided with main anodes 2, exciting anodes 3, a cathode 4 and a starting anode 5. Current is supplied to the exciting anodes 3 from a suitable source through a 35 transformer 6 comprising a secondary winding which has its end terminals connected to the exciting anodes 3 and is connected at a point intermediate its ends to the cathode 4 through impedance devices shown as resistors 14, 15 and 16.

A thermal responsive device 7 operable in response to the current produced by a thermo-electric pile 8 mounted within or adjacent to the rectifier 1 is arranged to control 40 the connections of the resistors 15 and 16 in accordance with the temperature of the rectifier. The device 7 is provided with a movable member 9 which may be utilized to indicate the temperature of the rectifier

and with contacts 10 and 11 which are arranged to engage a contact mounted on the end of the member 9 for the purpose of completing circuits whereby the operating coils 12 and 12' are respectively connected to sources of current shown as batteries 13 and 13'.

The operation of the apparatus will be readily understood if it be assumed that the transformer 6 is energized but the temperature of the rectifier 1 is too low to permit starting of its exciting current at the existing temperature. Under these conditions, the contact on the end of the member 9 is moved either into engagement with the contact 10, or with the contact 11. When the contact of the member 9 engages the contact 10, the operating coil 12 is energized and the resistor 16 is short-circuited by the switch 17, thus increasing the potentials applied to the starting and exciting anodes. 75 If this increase in potential is insufficient to start the arc of the rectifier at the existing temperature, contact is made between the end of the member 9 and the contact 11, thus producing closure of the switch 18 whereby the resistors 15 and 16 are both short-circuited and the starting and exciting anode potentials are increased to a point at which starting of the arc is ensured.

Likewise, if the temperature of the rectifier decreases during its operation, interruption of the arc is prevented by the increase in exciting anode potential produced by operation of the switches 17 and 18. My invention thus provides a simple and reliable 90 means whereby starting and operation of the rectifier is rendered to a large degree independent of the ambient temperature.

The embodiment of the invention illustrated and described herein has been selected 95 for the purpose of clearly setting forth the principles involved. It will be apparent, however, that the invention is susceptible of being modified to meet the different conditions encountered in its use and I therefore 100 aim to cover by the appended claims all modifications within the true spirit and scope of my invention.

What I claim as new and desire to secure by Letters Patent of the United States, is:— 105

1. The combination of a vapor electric device comprising exciting electrodes, means arranged to apply a potential to said elec-

trodes, and means operable to control said potential in accordance with the temperature of said device.

2. The combination of a vapor electric device comprising exciting electrodes, means arranged to apply a potential to said electrodes, a thermal responsive element arranged to operate in accordance with the temperature of said device, and means for varying the magnitude of said potential in response to the operation of said element.

3. The combination of a vapor electric device comprising exciting electrodes, means arranged to apply a potential to said electrodes, a thermal responsive element mounted within the casing of said device, and means arranged to vary said potential in accordance with the operation of said element.

20 4. The combination of a transformer comprising a winding provided with a plurality of terminals, a vapor electric device provided with an electrode connected to one of

said terminals and with a cathode, an impedance element connected between said cathode and another of said terminals, and means arranged to control the connections of said impedance element in accordance with the temperature of said vapor electric device.

30 5. The combination of a transformer comprising a winding provided with end and intermediate terminals, a vapor electric device provided with an exciting anode connected to an end terminal and with a cathode, a plurality of impedance elements connected between said cathode and said intermediate terminal, and means arranged to progressively control the connection of said impedance elements in response to variation in the temperature of said vapor electric device.

In witness whereof, I have hereunto set my hand this 20th day of September, 1926.

YOSINOBU MATUNAGA.
